TOY CAP RIFLE

Benjamin Eulénfeld, St. Simón Island, Ga.

Application February 17, 1948, Serial No. 8,850

9 Claims. (Cl. 42—57)

1

This invention relates to an amusement device or toy for children and is specifically directed to improvements on a gun adapted to fire conventional fulminate tape and has for its primary object to provide a toy gun, simulating a real rifle, within which is mounted an operating mechanism for firing rolls of caps or such similar tape.

Another object of this invention is to provide a cocking and feeding mechanism and cap-firing or exploding mechanism which is combined with a conventional and customary rifle.

Another object of this invention is to provide a roll cap rifle which is constructed of few parts, economical to manufacture, reliable and durable in use and, also, safe and harmless in character.

These and ancillary objects, to become more apparent, are attained by this invention, a preferred embodiment of which is set forth in the following description and illustrated in the accompanying drawings, wherein:

Figure 1 is a side elevational view of a rifle, having mounted therein, a cap-exploding mechanism, both constructed in accordance with the principles of this invention;

Figure 2 is an interior side elevational view of the operating mechanism, with one of the breech plates removed and showing the working parts in normal position, after firing;

Figure 3 is an interior elevational view of the working parts showing the parts in cocked position;

Figure 4 is a top plan view showing the breech plates attached;

Figure 5 is a vertical end view of the assembly showing the breech plates attached;

Figure 6 is an elevational side view of the interior of one of the breech plates;

Figure 7 is an elevational side view of the exterior of one of the breech plates; and,

Figure 8 is a view in perspective of the anvil.

Referring now more particularly to the drawings, wherein similar characters of reference designate corresponding parts throughout there is shown, with reference to Figure 1, a rifle, generally denoted by numeral 10, of conventional design and comprising a barrel 12 carried by a stock piece 14, preferably constructed of wood or the like.

Secured to the stock piece 14 by means of screws 16 adjusted through aligned horizontal apertures 18 and 20 are complementary breech plates 22 and 24.

Suitably mounted within the breech plates 22 and 24 is an anvil 26, as shown in Figure 8, hav-

2

ing an arcuate terminating portion 28. Axial bores 30 and 32 are provided transversely in the anvil head portion 34, and a set screw 36 in bore 32 serves to secure the anvil to the interior of breech plate 22, with the head portion flush beneath a longitudinal marginal flange 38, disposed integral with the plate. The arcuate terminal 28 defines a cap chamber, for roll caps 40, which are received therein on a lateral pin 42, which projects from the plate 22 and are fed around the arcuate section 28 upwardly into placement in registry with the side of the head portion 34 of the anvil 26.

Pivoted secured within the breech plates 22 and 24 in striking alignment with the anvil 26 is a firing hammer 44 having an upstanding fiberpiece 46 and a substantially circular integral offset portion 48, through which a pivot pin 50 is journaled, the pivot pin extending laterally between the breech plates and secured to the inner sides thereof. Extending from the offset portion 48 is a projecting tongue 52, which extends rearwardly between the breech plates and is seated on the extending portion of a spring bar 54, the opposite end of the bar being suitably inserted within a pair of stepped spring blocks 56 and 58. The oval portion 48 of the hammer 44 is suitably notched as at 60, below the tongue piece 52 and the notched portion 60 accommodates a lateral upstanding terminal portion of a sear 64, which is pivotally carried by a pivot pin 62, transversely journaled between the breech plates 22 and 24. The sear 64 is constantly maintained in sliding engagement with the periphery of the oval portion 48 by a spring bar 66, which has one end positioned beneath the sear, the opposite end being retained in a spring block 68 by a rivet 70 or the like.

The sear 64 extends forwardly and the terminating portion thereof is received on a shoulder portion 70 of a trigger 72, which is pivoted as at 74 to the breech plates and which depends below the breech plates 22 and 24 through a suitable opening 76 formed in the bottom juncture thereof. A stop 78 is transversely secured in forward proximity to the trigger 72.

Means are provided for cocking the hammer 44 and includes a cocking lever 82, having an elongated handle loop 84 on the rearward extremity thereof and pivoted by a swivel pin 86 to the breech plates. Extending from the pivot point 86 between the breech plates and integral with the lever 82 is a semi-lateral arm extension 90, which has its extremity suitably apertured and pinned as at 92 to a cocking bar 94. Later-

ally projecting and extending upwardly from the bar 94 is an actuating arm 96, which is engaged by a spring bar 98, suitably secured to a spring block 100.

Projecting rearwardly from the terminus of the cocking bar 94 opposite the pivoted end is a hammer actuating finger 102, which is received within a V-shaped notch 104 disposed in the oval pivoted section 48 of the hammer 44.

Loading means are provided in association with and controlled by the cocking mechanism and includes a cap feeding lever 106, having one end pinned as at 108 to an offset portion 110 of the cocking bar 94 and the other end angularly bent forming a feeding finger 112, which engages the cap roll 40 on the side of the anvil 26. A coil expansion spring 114 is secured to the lever 106 at one end and to the medial body portion of the cocking bar 94 at the other and serves to yieldingly bias the feeding finger 112 relative to the anvil.

In operation, the cocking lever 82 is moved downwardly by manual power applied to the handle terminus 84 and is moved about its pivot point 86. Respondingly, the cocking bar 94 is moved upwardly causing the simultaneous movement of the cap roll upwardly, through the medium of the loading lever 106, and the cocking of the hammer 44, which is moved back on pin 50 by the urging engagement of the cocking bar finger 102 with the peripheral notch 104.

As the hammer 44 moves back, the sear 64 engages the notch 60 in the oval section 48 and locks the hammer in a cocked position, as shown in Figure 3.

Thus, the lever handle 84 may be moved back into placement on the bottom of the breech plates and the gun is readied for use, with a suitable loaded portion of the fulminate tape 40 positioned in alignment with the anvil and hammer.

Manual pressure applied on the trigger 72, rocks the sear 64 on its pivot pin 62 and moves it out of engagement with the hammer notch 60. Then, the spring bar 54 biases or urges the hammer forward causing it to strike forcibly against the anvil 26 and thusly exploding the cap. A swivel plate 116 is secured to the breech plates 22 and 24, and covers the top juncture thereof. The plate is pivoted by means of apertured integral ears 118, which extend forwardly and receive a pin 120, to the plates and provide ingress to the cap chamber for replacing the roll of caps 40, when the roll is exhausted.

Thus, it is apparent that there is provided a reliable, dependable and efficient cap rifle, wherein novelty is believed to reside in the combining of a rifle and the above described loading, cocking and firing mechanism and also, in the mechanism itself.

However, since many other modifications and purposes of this invention will become readily apparent to those skilled in the art upon a perusal of the foregoing description it is to be understood that certain changes in style, size and components may be effected without a departure from the spirit of the invention and within the scope of the appended claims.

Having described the invention, what is claimed as new is:

1. In a toy gun simulating a rifle, a fulminate tape exploding mechanism comprising an anvil, having an arcuate extension defining a casing for a cap chamber, a hammer pivoted in alignment with said anvil, cocking means for said

hammer, means for holding said hammer in a cocked position reciprocating means carried by said cocking means for withdrawing tape from the chamber and feeding the same about the arcuate extension into alignment between the anvil and hammer, means for retaining said reciprocating means in engagement with said anvil and means for releasing said holding means from the hammer and means responsive to said last means for urging the hammer into striking engagement of said anvil.

2. In a toy gun simulating a rifle, a stock, a breech chamber, an anvil mounted in said chamber, an arcuate extension on said anvil for housing a roll of tape, a hammer pivoted in said chamber in striking alignment with said anvil, means for cocking said hammer, means for holding said hammer in a cocked position means carried by said cocking means for feeding tape from the arcuate extension into an explodable position between the anvil and the hammer, resilient means for maintaining said tape feeding means in contact with said anvil means for releasing said holding means from said hammer and means responsive to said last means for urging said hammer into striking engagement of said anvil.

3. In a toy gun simulating a rifle, a stock, a breech chamber, breech plates for said chamber, an anvil mounted between said breech plates, an arcuate extension on said anvil for housing a roll of tape, a hammer pivoted between said breech plates in firing registry with said anvil, a cocking lever pivoted at one end between the breech plates and having its opposite end disposed below said plates, means for cocking said hammer actuated by said cocking lever, means for holding said hammer in a cocked position reciprocatory tape feeding means carried by said cocking means and disposed in sliding engagement of said arcuate extension, anvil and means for releasing and firing said hammer, a tape chamber ingress opening in one of said breech plates and a pivoted closure plate for said opening.

4. In a toy gun for exploding fulminate tape, a stock, a breech chamber in said stock, breech plates for said chamber, an anvil mounted between said plates, a housing for a roll of tape extending from said anvil, a hammer pivoted between said breech plates in striking registry with said anvil, a cocking lever pivoted between said breech plates, a cocking rod actuated by said lever and adapted to bear against and move said hammer into a cocked position tape feeding

means carried by said rod for feeding tape between said anvil and hammer, means for holding said hammer in a cocked position means for maintaining said tape feeding means in contact with the outer surface of the tape housing, means for releasing said holding means from said hammer and means for urging said hammer into striking contact of the anvil.

5. In a toy gun simulating a rifle, a stock, a breech chamber in said stock, breech plates for said chamber, an anvil mounted between said plates, a housing for a roll of tape extending from said anvil, a hammer pivoted between said breech plates in striking registry with said anvil, a cocking lever pivoted at one end between the breech plates, an extension on said cocking lever beyond the pivot point, a cocking bar pivoted at one end to said extension and bearing against the hammer at its other end to cock the hammer, holding means for retaining the hammer in a cocked position, a tape feeding finger pivotally

carried by said bar, means connected between said bar and finger for maintaining the finger in sliding contact with the tape housing for feeding tape from said housing upwardly into an explodable position on the anvil in front of the hammer, means for releasing the holding means from the hammer and means responsive to said last means for urging said hammer into striking engagement of the anvil.

6. The combination of claim 5, wherein said feeding finger terminates in an arcuate point slidably engaged on the housing. 10

7. The combination of claim 5, wherein said means for maintaining said finger in engagement with the housing includes a spring anchored to the finger and cocking bar. 15

8. The combination of claim 5, wherein said feeding finger is pivoted to a lateral extension on said cocking bar.

9. The combination of claim 5, wherein a spring bar is anchored at one end between said breech plates and terminates in a free end engaged on said cocking bar for maintaining the bar and feeding finger under compression and urging the same forwardly and upwardly upon actuation of the cocking lever.

BENJAMIN EULENFELD.
